UNITED STATES PATENT OFFICE.

THURE DAHL, OF BROOKLYN, NEW YORK, ASSIGNOR TO LIGHTOLIER COMPANY, OF NEW YORK, N. Y., A CORPORATION OF NEW YORK.

DESIGN FOR A BRACKET-BACK.

14,737.

Specification for Reissued Design. Reissued Oct. 14, 1919.

Original No. 53,004, dated February 18, 1919, Serial No. 260,614, filed October 31, 1918, for 7 years. Application for reissue filed March 26, 1919. Serial No. 285,401. Term of patent 7 years.

To all whom it may concern:

Be it known that I, THURE DAHL, residing and having my post-office address at #328 73d street, borough of Brooklyn, 5 county of Kings, State of New York, and a subject of the King of Sweden, have invented a new, original, and ornamental Design for Bracket-Backs, of which the following is a specification, reference being had to 10 the accompanying drawing, forming part thereof.

Figure 1 is a face view, and Fig. 2 is a side elevation of a bracket back, showing my new design.

I claim: 15
The ornamental design for a bracket back as shown.

THURE DAHL.

Witnesses:

DAVID HAAR,
MOSES D. BLITZER.
